(57) **CLAIM**

The ornamental design for a stationary exercise apparatus, as shown and described.

DESCRIPTION

FIG. 1 is a perspective view of our new stationary exercise apparatus;

FIG. 2 is a left side elevational view of the stationary exercise apparatus;

FIG. 3 is a right side elevational view of the stationary exercise apparatus;

FIG. 4 is a front elevational view of the stationary exercise apparatus;

FIG. 5 is a rear elevational view of the stationary exercise apparatus; and,

FIG. 6 is a top plan view of the stationary exercise apparatus. The phantom line showing environment is for illustrative purpose only and forms no part of the claimed design.
